US0D1095625S

(12) **United States Design Patent** (10) **Patent No.:** **US D1,095,625 S**
Chen (45) **Date of Patent:** **** Sep. 30, 2025**

(54) **3D PRINTER**

(71) Applicant: **Moxin (Huzhou) Technology Co., LTD.**, Huzhou (CN)

(72) Inventor: **Tianrun Chen**, Huzhou (CN)

(73) Assignee: **Moxin (Huzhou) Technology Co., LTD.**, Huzhou (CN)

(**) Term: **15 Years**

(21) Appl. No.: **29/871,954**

(22) Filed: **Mar. 2, 2023**

(30) **Foreign Application Priority Data**

Nov. 30, 2022 (CN) 202230800320.0

(51) **LOC (15) Cl.** **15-09**

(52) **U.S. Cl.** **D15/122**
USPC .....

(57) **CLAIM**

The ornamental design for a 3D printer as shown and described.

DESCRIPTION

FIG. 1 is a perspective view of a 3D printer showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the 3D printer that form no part of the claimed design. The KOKONI logo, which forms no part of the claimed design, is a registered trademark of Moxin (Huzhou) Tech. Co., LTD.

1 Claim, 8 Drawing Sheets
